Primary Examiner — Angela J Lee*(74) Attorney, Agent, or Firm* — Suiter Swantz pc llo(57) **CLAIM**

The ornamental design for the electronic tablet support, as shown and described.

DESCRIPTION

FIG. 1 is a perspective view of an electronic tablet support, showing the new design;

FIG. 2 is a top plan view thereof;

FIG. 3 is a front elevation view thereof;

FIG. 4 is a first side elevation view thereof;

FIG. 5 is a rear elevation view thereof;

FIG. 6 is a second side elevation view thereof; and,

FIG. 7 is a bottom plan view thereof.

The broken line showing of an electronic tablet is included for the purpose of illustrating environment and forms no part of the claimed design.
